OPENING AND CLEANING OF FIBROUS MATERIALS

Thomas William Owen, Didsbury, Manchester, England, assignor to The British Cotton Industry Research Association, Manchester, England, a British association

Application April 17, 1947, Serial No. 742,057
In Great Britain May 13, 1946

11 Claims. (Cl. 19—79)

1

The present invention relates to machines for opening and cleaning of fibrous materials particularly of cotton at an early stage in the complete series of opening and cleaning processes, for example, at the stage when it comes directly from the bale, and of the type in which a sloping spiked lattice carries the fibrous material upwards from a bin or hopper to the highest point of the lattice, where a spiked roller, known as an evener roller or regulating cylinder, strikes back a certain proportion of the material and allows the remainder to pass forward over the highest point of the spiked lattice, to be stripped from it by a beater operating against a grid or dirt bars, the beater effecting a certain degree of opening and cleaning and delivering the cotton usually either on to a further lattice or into a mouth piece coupled up to trunks or tubing. Familiar known forms of such machines are the different kinds of hopper bale openers and hopper feeders for cotton and the invention will be described with specific reference to these machines.

The object of the invention is an improved machine of the type aforesaid so as to obtain a higher degree of opening and cleaning and dust removal.

According to the invention a machine for opening and cleaning fibrous materials comprises a hopper and casing containing a sloped spiked lattice adapted to carry the fibrous material upward and below an evener roller and thence to a beater in another part of the casing, with stripper means for and adjacent to said evener roller and suction means for extracting dust from the upper part of the feed side of the hopper characterised in that the stripper means for the evener roller consists of a combined rotary suction cage and stripper whereby dust liberated from the fibrous material by the combined action of the evener roller and its stripper may be more effectively removed by removing it at the region of such liberation and without loss of useful fibre.

The machine aforesaid may be further characterised in that the combined rotary suction cage and stripper comprises a rotary suction cage, flaps on said cage adapted to act as strippers for the evener roller without holding the stripped material and a damper within the suction cage adapted to confine the suction to the portion of the cage periphery immediately facing the evener roller.

According to a further feature of the invention a machine for opening and cleaning fibrous materials comprises a casing, a beater housed

2

therein and working against dirt bars, and to which beater the material is fed by a spiked lattice characterised in that the casing is shaped without a stripper edge so that only a portion of the material is delivered by the beater for carrying forward, and so as to provide a space of substantial volume above the beater into which the remainder of the material is projected by the beater whereby at least some of it returns to the beater for further beating, means being provided such as a partition to prevent such projected material from being thrown into the region above the spiked lattice.

The machine last mentioned may be further characterised in that a plurality of beaters is provided arranged in series each without a stripping edge and so that each beater except the last of the series delivers some of the material forward to the adjacent succeeding beater and projects the remainder of the material into the space above the beaters from which it may return for further beating; or further characterised by a suction cage arranged to receive that portion of the material from the beater or last beater to be carried forward; or further characterised by at least one suction cage in the space above the beater or beaters for the extraction of dust liberated by the action of the beater or beaters projecting the material into the said space.

30. In the accompanying drawings:

Fig. 1 illustrates diagrammatically a machine for opening and cleaning fibrous material according to this invention;

Fig. 2 illustrates diagrammatically a modification of the machine shown in Fig. 1.

As shown in the drawings, the rearward portion 1 of the machine constitutes a hopper in which the horizontal lattice 2 feeds the cotton towards a spiked lattice 3. An evener roller 4, with spikes 4¹, is located above the spiked lattice 3 and allows a certain proportion of the cotton carried upwards by the lattice to pass forwards while the rest is projected back into the bin 1. These arrangements are usual in hopper openers and in many such machines a stripper is provided for the evener roller. In place of such a stripper a combined high speed suction cage and stripper 5 is provided. The suction cage is provided on its outer periphery with leather flaps 5¹ which

50. serve to strip any cotton which may adhere to the teeth 4¹ of the evener roller 4, and with radial dampers 5² which confine the suction to the portion 5³ of the periphery of the cage. In the region contiguous to the evener roller 4, the combined 55 cage and stripper 5 and the upper part of the

ascending portion of the spiked lattice 3, a considerable amount of dust is liberated, and this is sucked through the perforations of the combined cage and stripper 5. In machines of known kinds a similar liberation of fine dust occurs, but most of this is deposited back on to the cotton in the hopper. In Fig. 1 is illustrated diagrammatically a known method of dealing with this liberated dust, namely, by fan suction through a duct 6 located in the cover of the hopper. The efficiency of such means is greatly impaired by its remoteness from the region where the dust is liberated; and the amount of dust extracted is greatly increased by the more effectively localized suction at the portion 5³ of the cage 5. The means for localized suction may be adopted either with or without the above mentioned known means in the duct 6. The flaps 5¹ may be of any other suitable material instead of leather.

The cotton which is allowed to pass over the highest point of the spiked lattice 3 comes under the action of a beater 1. This is provided with serrated flaps 7¹ which serve to strip cotton from the spikes 3¹ of the spiked lattice 3, and also with spikes 7². The beater 1 works against dirt bars 7³ and, in respect to its features so far described, does not differ essentially from the kind of beater used in known forms of hopper opener. In such known forms, however, the cover fits closely to the beater and is provided with a stripping edge to ensure that practically all the cotton acted on by the beater is stripped from it and delivered to such means of further conveyance as may be adopted. In the example shown in the drawing a second beater 8 is provided without the intervention of a stripping edge for the first beater and in series with the first beater, with the result that cotton delivered by the first beater is only in part acted upon immediately by the second beater, the remainder being projected upwards into a region 9 provided under a cover 11 which is raised a substantial distance at least equal to the diameter of the beater, as shown in the drawings above the beaters and has no stripping edge for the second beater. The beater 8 is provided with spikes 8¹ and works against dirt bars 8².

The cotton after passing through the space between the periphery of the beater 8 and the dirt bars 8² comes under the action of a high speed suction cage 10. This is provided with radial dampers 10¹ confining the suction to the region 10² of its periphery. Owing to the absence of a stripping edge for the beater 8, only a portion of the cotton delivered by the beater 8 is carried forward immediately by the cage 10, or falls on to it from the cover 11, the remainder being projected into the region 9, so that it falls back on to either or both of the beaters.

The region 9 is bounded above by the portion 11 of the cover of the machine. This portion is shaped to bend downwards from the level of the horizontal portion 12 of the cover over the evener roller 4 to a point roughly in the level of the highest point of the cage 10.

As shown in Fig. 1 of the drawing, an upwardly extending partition 13 is provided within the casing that substantially divides the same into a beating compartment and a hopper compartment, said partition having an aperture 13^b affording limited intercommunication between said compartments, the upper section of the partition above the aperture 13^b being straight and separating the region 9 from the region below the portion 12 of the cover in which the evener roller

is located while allowing room for the passage of the cotton to the beater 7. The upper straight section of the partition occupies, relative to the evener roller a position roughly the same as that occupied in known forms of hopper feeders by a vertical portion of the outer cover.

Owing to the fan action of the beaters 7 and 8 the air in the region 9 is maintained in a state of considerable turbulence, and becomes filled with a mass of cotton in the form of tufts of various sizes, many of which are thrown with considerable violence against the cover 11 and partition 13. All this cotton is ultimately delivered from the machine by the suction cage 10, but much of it is subjected two or more times to the action of the beaters 7 and 8 and the cage 10. The violent agitation in the space above the beaters, repeated beater action, and cage suction to which the cotton is thus subjected at its several stages gives an opening and cleaning effect much superior to that obtained with the known forms of hopper feeder.

Fig. 2 illustrates an alternative form of the invention embodying cage suction within the region 9 in addition to the characteristic features described above. In this modification the cover is shaped to accommodate at 11¹ the upper part of a high speed cage 14; and this is provided with adjustable radial dampers 14¹ which confine the suction to the portion 14² of the periphery of the cage.

To meet varying requirements, it is preferable to make the depth of the straight vertical upper section of the partition 13 variable by such means as an adjustable part or end-piece 13¹, and to provide a means for varying the position of the terminal edge of the cover 11 adjacent to the cage 10, for example, by an adjustable end piece 11², or by interchangeable end-pieces of different shapes and sizes.

I declare that what I claim is:

1. A machine for opening and cleaning fibrous materials, comprising a casing, a partition disposed in said casing and substantially dividing the same into a beating compartment and a hopper compartment, said partition having an aperture affording limited intercommunication between said compartments, a spiked lattice disposed in sloping position in said hopper compartment for carrying fibrous material upward to the aperture in the partition, an evener roller mounted for rotation in the hopper compartment above the upper end of the lattice in position to remove surplus material from the lattice thereby to determine the thickness of material carried forward on the lattice, a rotary stripper disposed in said casing above the lattice and adjacent said evener roller in position to return the said surplus material to the said lattice, and a rotatable beater and dirt bars cooperating therewith disposed in the beating compartment in position to receive material from the spiked lattice through the said aperture, said rotary stripper comprising a rotary suction cage having stripping members mounted on its periphery, the organization being such that dust liberated from the fibrous material by the combined action of the evener roller and said stripper members is removed by the suction cage at the region of such liberation.

2. A machine according to claim 1, said beating compartment having an upper wall at all points spaced away from the beater a distance at least equal to the diameter of said beater thereby to provide a substantial space above the beater.

3. A machine according to claim 1, said beating

compartment having an upper wall at all points spaced away from the beater a distance at least equal to the diameter of said beater thereby to provide a substantial space above the beater, at least one additional beater being disposed in the beating compartment in series with said first beater whereby each beater except the last of the series delivers some of the material forward to the adjacent succeeding beater and projects the remainder of the material into the space above the beaters from which some of it returns to the said beaters for further beating.

4. A machine according to claim 1, said beating compartment having an upper wall at all points spaced away from the beater a distance at least equal to the diameter of said beater thereby to provide a substantial space above the beater, at least one additional beater being disposed in the beating compartment in series with said first beater whereby each beater except the last of the series delivers some of the material forward to the adjacent succeeding beater and projects the remainder of the material into the space above the beaters from which some of it returns to the said beaters for further beating, a suction cage being disposed in the beating compartment in position to receive material from the last beater for collection and delivery of the material from the beating compartment.

5. A machine according to claim 1, said beating compartment having an upper wall at all points spaced away from the periphery of the beater a distance at least equal to the diameter of the said beater thereby to provide a substantial space above the beater, a high speed suction cage being disposed in the space above the beater in position to extract dust from the material projected into said space by the beater.

6. A machine according to claim 1, said beating compartment having an upper wall at all points spaced away from the beater a distance at least equal to the diameter of said beater thereby to provide a substantial space above the beater, said partition having an adjustable part for varying the size of its aperture.

7. A machine for opening and cleaning fibrous materials comprising a casing, a partition disposed in said casing and substantially dividing the same into a beating compartment and a hopper compartment, said partition having an aperture affording limited intercommunication between said compartments, a spiked lattice disposed in sloping position in said hopper compartment for carrying fibrous material upward to the aperture in the partition, an evener roller mounted for rotation in the hopper compartment above the upper end of the lattice in position to remove surplus material from the lattice thereby to determine the thickness of material carried forward on the lattice, a rotary stripper disposed in said casing above the lattice and adjacent said evener roller in position to return the said surplus material to the said lattice, and a rotatable beater and dirt bars cooperating therewith disposed in the beating compartment in position to receive material from the spiked lattice through the said aperture, said beating compartment having an upper wall spaced away at all points from the periphery of the beater a distance at least equal to the radius of the said beater thereby to provide a substantial space above the beater, and a high speed suction cage disposed in the said space of the beating compartment above the beater in position to extract dust liberated by the ac-

tion of the beater projecting the material into the said space.

- 8. A machine for opening and cleaning fibrous materials, comprising a casing, a partition disposed in said casing and substantially dividing the same into a beating compartment and a hopper compartment, said partition having an aperture affording limited intercommunication between said compartments, a spiked lattice disposed in sloping position in said hopper compartment for carrying fibrous material upward to the aperture in the partition, an evener roller mounted for rotation in the hopper compartment above the upper end of the lattice in position to remove surplus material from the latter thereby to determine the thickness of material carried forward on the lattice, a rotary stripper disposed in said casing above the lattice and adjacent said evener roller in position to return the said surplus material to the said lattice, and a rotatable beater and dirt bars cooperating therewith disposed in the beating compartment in position to receive material from the spiked lattice through the aperture, said beating compartment having an upper wall spaced away at all points from the periphery of the beater a distance at least equal to the diameter of the said beater thereby to provide a substantial space above the beater and a high speed suction cage disposed in the said space
- 9. A machine for opening and cleaning fibrous materials as set forth in claim 7, at least one additional beater being disposed in the beating compartment in series with said first beater whereby each beater except the last of the series delivers some of the material forward to the adjacent succeeding beater and projects the remainder of the material into the said space above the beaters from which some of it returns to the said beaters for further beating.

- 10. A machine for opening and cleaning fibrous materials, comprising a casing, a partition disposed in said casing and substantially dividing the same into a beating compartment and a hopper compartment, said partition having an aperture affording limited intercommunication between said compartments, a spiked lattice disposed in sloping position in said hopper compartment for carrying fibrous material upward to the aperture in the partition, an evener roller mounted for rotation in the hopper compartment above the upper end of the lattice in position to remove surplus material from the latter thereby to determine the thickness of material carried forward on the lattice, a rotary stripper disposed in said casing above the lattice and adjacent said evener roller in position to return the said surplus material to the said lattice, and a rotatable beater and dirt bars cooperating therewith disposed in the beating compartment in position to receive material from the spiked lattice through the said aperture, said beating compartment having an upper wall spaced away at all points from the periphery of the beater a distance at least equal to the diameter of the said beater, said partition having an adjustable part for varying the size of its aperture.

- 11. A machine for opening and cleaning fibrous materials as set forth in claim 7 and including at least one additional beater disposed in the beating compartment in series with the first or receiving beater whereby each beater except the

last of the series delivers some of the material forward to the adjacent succeeding beater and projects the remainder of the material into the said space above the beaters from which some of it returns to the said beaters for further beating, and further including a suction cage disposed in the beating compartment to receive material from the last beater for collection and delivery of the material from the beating compartment.
